Patented July 1, 1969

214,558

FOLDABLE STEP UNIT FOR USE ON A MOTOR VEHICLE

Ralph D. Mulford, 935 Chipeta Ave.,
Grand Junction, Colo. 81501

Filed Oct. 9, 1967, Ser. No. 8,909

Term of patent 14 years

Int. Cl. D12—14

U.S. Cl. D15—8

FIG. 1

FIG. 2

FIG. 3

FIGURE 1 is a perspective view of a foldable step unit for use on a motor vehicle showing my design;

FIGURE 2 is a front elevational view; and

FIGURE 3 is a side elevational view thereof.

I claim:

The ornamental design for a foldable step for use on a motor vehicle, as shown.
